CLAIM

We claim the ornamental design for a device for level measurement, as shown and described.

DESCRIPTION

FIG. 1 is a left side view of the design;

FIG. 2 is a right side view of the design;

FIG. 3 is a top view of the design;

FIG. 4 is a bottom view of the design;

FIG. 5 is a front view of the design;

FIG. 6 is a back view of the design; and,

FIG. 7 is a perspective view of the design.
